AUXILIARY LADDER LEG

Filed Oct. 6, 1942

UNITED STATES PATENT OFFICE

2,320,144

AUXILIARY LADDER LEG

Eric Johnson, Brodhead, Wis.

Application October 6, 1942, Serial No. 461,001

2 Claims. (Cl. 228—63)

This invention relates generally to the class of ladders and scaffolds, and pertains particularly to an improved detachable and adjustable foot-piece or leg extension, a principal object of the invention being to provide such an extension or foot-piece for attachment to the lower end of a leg of a ladder or a scaffold support, which may be readily shifted upon the leg for levelling the ladder or scaffold and which may also be readily removed for application to another leg without having to shift the ladder.

Another object of the invention is to provide a detachable leg extension or foot-piece for a ladder, having a novel clamping unit by which the extension or foot-piece may be easily and quickly secured in adjusted position or released when desired.

Still another object of the invention is to provide an adjustable or extensible foot-piece for a ladder leg or for a supporting standard of scaffolding in which the clamping means by which the extension or foot-piece is secured in place can be entirely disconnected from the ladder leg or from the standard so as to be conveniently shifted to another working position without having to move the ladder or standard.

The invention will be best understood from a consideration of the following detailed description taken in connection with the accompanying drawing, it being understood, however, that the invention is not to be considered as limited by the specific illustration or description but that such illustration and description constitute a preferred embodiment of the invention.

In the drawing:

Figure 1 is a view in elevation of the bottom portion of a ladder showing the adjustable or extensible foot-piece constituting the present invention.

Figure 2 is a sectional view taken on the line 2—2 of Figure 1.

Figure 3 is a sectional view taken on the line 3—3 of Figure 1.

Figure 4 is a view in perspective of the clamping unit per se.

Referring now more particularly to the drawing the reference character L generally designates a ladder having the usual side pieces or legs 10 and the intermediate connecting rungs 11.

While the device embodying the present invention has been illustrated upon a leg of a ladder, it is to be understood that the invention is not to be limited in its use by reason of such illustration as it will be readily apparent that it

may be easily and quickly applied to supporting standards of scaffolds and to other similar supports or standards where an extension means may be of value to level structure supported by the standard.

In accordance with the present invention there is provided a length of material, which is preferably wood although it may be of any other substance, indicated generally by the numeral

10, and constituting an auxiliary leg or foot which is designed to be positioned against the outer side of the ladder leg in the manner illustrated. Adjacent one end of this auxiliary leg there is secured transversely of the wider face 15 thereof the substantially U-shaped guide bracket 13 which consists of the central bar portion 14 and the angularly turned spaced parallel legs 15 which are directed away from the side of the auxiliary leg 12 to which the bracket is attached so as to receive or embrace the ladder leg 10, as illustrated more particularly in Figure 2.

Adjacent its opposite end the auxiliary leg 12 has secured thereto the clamping unit which is indicated generally by the reference character 25, and which is shown or illustrated in detail in Figure 4. This clamping unit comprises a fixed elongated plate 17 which is disposed transversely of the wide face of the leg 12 opposite from the bracket 13 and is secured to the auxiliary leg by screws 18, or in any other suitable manner, as shown in Figure 3. As is also shown in this figure, the ends of the fixed clamp plate 17 projects beyond the sides of the auxiliary leg 12 and these extended ends have apertures 19 formed therethrough.

35 The numeral 20 generally designates a U-bolt having the yoke portion 21 and the spaced parallel legs 22. These legs are extended through the openings 19 of the fixed plate 17 so that the auxiliary leg is straddled by the U-bolt and the legs 22 of the U-bolt are of sufficient length to also extend entirely across the adjacent ladder leg, as shown in Figure 3, and are screw-threaded to receive securing nuts 23.

40 In spaced parallel relation with the fixed plate 17 is the elongated shiftable clamp plate 24, one end of which has an aperture 25 to receive one of the U-bolt legs 22, while the opposite end has a slot 26 formed from one side edge so as to facilitate the connection of the said other end with the other leg 22, as shown in Figure 4. Thus, the shiftable plate 24 functions in the nature of a latch member to couple the free ends of the legs of the U-bolt together. As will be readily apparent, the plates 17 and 24 have the auxiliary leg

and the adjacent ladder leg interposed therebetween so that the clamp unit forms a collar around these two elements and when the nuts 23 are drawn up upon the legs of the U-bolt the ladder leg and auxiliary leg will be drawn together when the yoke portion 21 of the U-bolt is held against movement with respect to the fixed plate 17.

As shown in Figure 3, the yoke portion 21 of the U-bolt is normally spaced from the plate 17 by means of the eccentric or cam head 27 which is formed at one end of a lever 28 and eccentrically mounted upon the yoke 21 of the U-bolt. When the lever 28 is shifted to a position where it is substantially parallel with the auxiliary leg 12 the high point of the cam will be interposed between the yoke 21 and the fixed plate 17, thereby shifting the legs of the U-bolt through the apertures 19 of the fixed plate and drawing the plates 17 and 24 together to firmly frictionally bind the auxiliary leg or foot and adjacent ladder leg together. When an adjustment of the auxiliary leg is to be made upon the ladder leg the cam head 27 of the lever is oscillated to remove the high point of the cam from between the yoke 21 and the plate 17, thereby permitting the yoke of the U-bolt to shift toward the plate 17 and freeing the frictional contact between the auxiliary leg and adjacent ladder leg. Thus the auxiliary leg may be extended longitudinally of the ladder leg to the necessary extent to level the ladder.

If it is desired to shift the auxiliary leg to the opposite leg of the ladder without having to move the ladder this may be readily done, after the binding clamp 27 is loosened in the manner described, by swinging the shiftable plate 24 so that the end thereof having the aperture 25 there-through will turn upon the adjacent bolt leg and the other bolt leg will be freed from the slot 26. Thus the auxiliary leg can be taken away from the ladder leg and replaced against the outer side of the opposite ladder leg, the shiftable plate 24 reengaged between the free ends of the U-bolt legs and the binding cam returned to operative position to secure the auxiliary leg and ladder leg together after the desired adjustment of the auxiliary leg has been accomplished.

This feature of the device by which the auxiliary leg can be readily shifted from one side of the ladder to the other is of particular advantage when using the device upon an extension ladder because of the fact that such ladder cannot be

turned around as in the case of a single or one length ladder. Also, as previously described, it can be put on or taken off without having to lift the ladder leg from the ground.

It will also be obvious that the use of a device of the character herein described upon a ladder leg affords greater safety than is afforded by the usual procedure of building up an extra support under the lower end of the ladder leg where the ladder has to be placed upon uneven or sloping ground, or with one end upon a step or other structure.

I claim:

1. In a supporting structure such as a ladder, scaffold and the like, having a supporting standard, an auxiliary leg for attachment to said standard, comprising an elongated member designed to be disposed against one side of the standard, means carried by the member for sliding engagement with the standard forming a guide, and a clamping unit for frictionally securing the member and standard together against relative movement, comprising an elongated plate disposed transversely of one side of the member remote from the standard and secured to the member and having ends projecting beyond the adjacent sides of the member, said projecting ends having guide apertures, a U-bolt having a yoke portion and spaced parallel legs, said legs being extended through the apertures of said plate whereby the legs are extended across the member and the adjacent standard, the yoke being adjacent to and in parallel relation with the plate, a second plate connected between the legs of the U-bolt and disposed across the side of the standard remote from the member, removable securing means carried by the ends of the U-bolt legs and engaging against the second plate, a lever, and an eccentric head oscillatably supported upon said yoke and bearing against the first plate, said head functioning, upon oscillation of the lever in one direction, to draw the member and standard into firm frictional engagement.

2. In a supporting structure such as a ladder, scaffold and the like, an auxiliary support as set forth in claim 1, in which the second-mentioned plate is engaged at one end with the adjacent bolt leg through the medium of a slot cut therein whereby the second plate functions as a shiftable latch by which disconnection of the clamp unit from the standard may be effected.

ERIC JOHNSON.
